UNITED STATES PATENT OFFICE.

HOWARD M. BARBER, OF WESTERLY, RHODE ISLAND, ASSIGNOR TO C. B. COTTRELL & SONS COMPANY, OF WESTERLY, RHODE ISLAND, A CORPORATION OF DELAWARE.

TYMPAN CLAMP.

Application filed November 13, 1925. Serial No. 68,821.

In ordinary web printing where comparative wide margins are left across the web between successive printed portions, the longitudinal slot through the shell of the impression cylinder can be made amply wide to permit the make-ready tympan clamp to be turned back into the cylinder without shifting its axis for putting on or removing the tympan. However, in some classes of web printing it is necessary to leave very narrow margins across the web between the printed portions and this makes it necessary to make the longitudinal slot through the cylinder shell so narrow that the tympan clamp cannot be turned back into the cylinder on a fixed axis. Therefore, I have provided means whereby the axis of the tympan clamp may be moved inwardly, when desired, to a point where the clamp can be turned back within the cylinder and thus leave the slot unobstructed, it being understood that the axis is brought back to its normal position when the leading edge of the tympan is to be clamped.

25 A practical embodiment of my invention is represented in the accompanying drawings, in which

Fig. 1 represents a detail view in side elevation of so much of an impression cylinder as includes my invention.

Fig. 2 represents a detail section taken in the plane of the line II—II of Fig. 3.

Fig. 3 represents a detail end view of the cylinder.

35 Fig. 4 represents a detail section taken in the plane of the line IV—IV of Fig. 2.

Figs. 5, 6 and 7 represent detail end views showing the tympan clamp in different positions.

40 The shell of the impression cylinder is denoted by 1 and its ends by 2. The shell 1 of the impression cylinder has a narrow longitudinal slot 3 therethrough. The cylinder is also shown as being provided with the usual shifting tympan mechanism which forms no part of the present invention and will not be specifically described herein.

Proceeding to describe the tympan clamp: The bushings 4 are rotatably mounted in the ends 2 of the cylinder, said bushings having lock plates 5 fixed thereto, exterior to the cylinder ends, as, for instance, by countersunk screws 6. Means are provided for locking these plates 5 and thereby the bushings 4 in their operative position, which means in

the present instance comprises hooks 7 which coact with bolts 8 projecting from the cylinder ends and their nuts 9.

The tympan clamp 10, which coacts with one wall of the slot 3 to clamp the leading edge of the make-ready tympan thereto, is provided with trunnions 11 and 12 which are eccentrically mounted in the bores of the bushings 4 at the opposite ends of the cylinder. The trunnion 12 is provided with a lever member 13 fixed to its end, as, for instance, by a set screw 14. The lever member 13 and thereby the tympan clamp 10 may be rocked, for instance, by providing the lever member with a hole 15 for receiving a removable lever 16.

The lock plates 5 and thereby the bushings 4 may be rocked, as, for instance, by providing the lock plates with holes 17 for the reception of a removable lever 18.

The free end of a spring 19, secured to one end of the cylinder as at 20, is arranged to engage the lever member 13 for holding the tympan clamp 10 in its operative position.

To release the tympan clamp I first disengage the free end of the spring 19 from its locking engagement with the lever member 13, allowing the parts to assume the positions shown in Fig. 5. The nuts 9 are 85 then loosened on their bolts 8 to unlock the bushing plates 5. The levers 18 may then be used to rock the plates and thereby the bushings to move the trunnions 11 and 12 of the finger 10 inwardly into the position shown in Fig. 6. The clamp 10 may then be rocked into the position shown in Fig. 7 to clear the slot 3 from all obstruction.

When the parts are in the positions shown in Fig. 7, it is obvious that the clamp 10 may 90 be turned back into the cylinder as far as necessary for the insertion and removal of the make-ready tympan. It will be understood that when the leading edge of the make-ready tympan is to be clamped to the side wall of the slot 3 the lock plates and their bushings are brought back to their operative position and there locked by tightening the nuts 9. The clamp is then closed, bringing the spring 19 into its position for 100 holding the clamp in its closed position until again released.

It is evident that various changes may be resorted to in the construction, form and arrangement of the several parts without de- 110

parting from the spirit and scope of my invention; hence, I do not intend to be limited to the particular embodiment herein shown and described, but

5. What I claim is:—

1. An impression cylinder, bushings rotatably adjustable therein, a tympan clamp having trunnions eccentrically mounted in said bushings, lock plates carried by the 10 bushings and means for locking the plates and thereby the bushings in their operative positions.
2. An impression cylinder, bushings rotatably adjustable therein, a tympan clamp 15 having trunnions eccentrically mounted in said bushings, lock plates carried by the bushings, means for locking the plates and thereby the bushings in their operative positions and a lever member carried by one of the 20 trunnions for use in rocking the clamp.
3. An impression cylinder, bushings rotatably adjustable therein, a tympan clamp having trunnions eccentrically mounted in said bushings, lock plates carried by the 25 bushings, means for locking the plates and

thereby the bushings in their operative positions, a lever member carried by one of the trunnions for use in rocking the clamp and means engaging the lever member for locking the clamp in its operative position.

4. An impression cylinder, bushings rotatably adjustable therein, a tympan clamp having trunnions eccentrically mounted in said bushings, lock plates carried by the bushings, means for locking the plates and thereby the bushings in their operative positions, a lever member carried by one of the trunnions for use in rocking the clamp and spring means engaging the lever member for locking the clamp in its operative 40 position.

5. An impression cylinder having a narrow longitudinal slot through its shell and a tympan clamp mounted to be moved bodily inward and rocked into a position 45 within the cylinder to clear said slot.

In testimony that I claim the foregoing as my invention, I have signed my name this 10th day of November, A. D. 1925.

HOWARD M. BARBER.
